CHARLES H. CHANDLER AND CHARLES L. CHANDLER, OF SEATTLE, WASHINGTON.

STRING-FASTENER.

No. 898,319.

Specification of Letters Patent.

Patented Sept. 8, 1908.

Application filed October 1, 1907. Serial No. 395,400.

To all whom it may concern:

Be it known that we, CHARLES H. CHANDLER and CHARLES L. CHANDLER, citizens of the United States, residing at Seattle, in the county of King and State of Washington, have invented certain new and useful Improvements in String-Fasteners, of which the following is a specification, reference being had therein to the accompanying drawings.

10 This invention relates to string-fasteners and especially to devices of this character which are intended for securing the lacings of shoes.

15 The object of our invention is the provision of simple and inexpensively constructed attachments for shoes, or other objects which are laced, and wherewith the strings may be readily and reliably secured without the employment of knots.

20 The invention consists in the novel construction, adaptation and combination of devices as will be hereinafter described and claimed.

In the drawings, Figure 1 is a face view of a string-fastener embodying our invention and illustrated with a string engaged thereby. Fig. 2 is a longitudinal view of the same without the string. Figs. 3 and 4, respectively, are perspective views of the 25 tongue and backing plate, such as are used in the device illustrated in the preceding views. Fig. 5 is a like view to Fig. 1 showing a modification in the manner of connecting the parts. Fig. 6 is a longitudinal section of Fig. 5. Figs. 7 and 8 are perspective views of the tongue and backing plate modified to conform to the invention as assembled in Figs. 5 and 6.

Referring first to Figs. 1 to 4, inclusive, 40 which illustrate the preferred manner of carrying out the invention, the numeral 10 represents a hook as ordinarily used with laced shoes and, as common, it is secured to the shoe-top 11 by riveting the inwardly protruding portion 15 which is punched from the hook-shank 12 over the inner surface of the shoe-top. In this instance, however, the portion 15 instead of being riveted immediately upon the top-leather is inserted 45 through an aperture of a backing-plate 13 and riveted over the latter. This plate is placed upon the inside of the shoe and extends in a horizontal direction for some dis-

tance from the hook and has, in proximity of its remote end an aperture to receive an eyelet 21 whereby such end is rigidly secured to the shoe-top and also to tongue-member 14 upon the outside of the leather. This member is of spring metal and formed with a flat end 14' which bears against the shoe and another flat end 14" which by offsetting through the bends 14''' serves to normally bear against the underside of the hook-bill 10'. The part 14" of the tongue member is apertured at 16 to accommodate the neck of 65 the hook and is extended therebeyond and terminates in a head 18 with oppositely directed horns 19 formed by recesses 17 upon opposite sides of a neck 17' which is between the head and main portions of the member. 70

The aforescribed embodiment of the invention is that best adapted for use where the same is to be incorporated in a shoe prior to its leaving the manufactory. With shoes, however, which are already provided with 75 hooks, the fastening attachments may be secured to the shoe in other ways so as not to disturb or loosen the hooks. According to such conditions, see Figs. 5 to 8, inclusive, we form the plate 13 with a hooked end 80 which is introduced through the eye of the hook-shank 12 and is secured by closing the plate-hook upon the intervening part of the shank and the shoe-top, as most clearly shown in Fig. 6. The other end of the plate 85 may be secured by an eyelet, as explained in the foregoing description of the preferred construction, or by inserting a tang 20 provided upon the end of the member 14 through an aperture 13" of the plate and 90 bending such tang over the latter. This construction affords means whereby the fastening attachments may be secured to a shoe by a person of ordinary ability.

To secure a lacing, or other string, A, with 95 this device the string, see Fig. 1, is passed about the neck 17' of the tongue-member 14, as at a, the free end is then led, as at a', to cross and overlie the part a and, finally, inserting the end between the hook-bill 10' and the tongue-member 14. When a string is thus engaged the resilience of the tongue is sufficient to prevent the accidental withdrawal of the extremity of the string which, in turn, confines the underlying part upon 100 105 the tongue-neck 17', and the greater the ten-

sion put upon the string from the other part the greater will be the security of the fastening thereof.

The invention is useful in providing a means for readily securing lacings without tying, and from which a string may be as readily loosened.

While the invention may be advantageously employed wherever laced shoes are used, it is notably valuable with children's shoes in obviating the tying and untying of knots.

Having described our invention, what we claim, is—

15 1. In a fastener of the character described, a tongue member formed of spring metal and having an aperture intermediate its length and recesses to one side thereof to provide a terminal head, combined with a fixedly-se-
20 cured hook projecting through the aperture in said tongue member, as and for the purpose described.

25 2. In a fastener of the character described, a backing-plate formed with a hook at one end and an aperture in proximity of its other end, a tongue member provided with a tang at one end for engagement with the plate through said aperture and having intermediate its length an aperture, and a fixedly-se-

cured hook projecting through the aperture 30 in said tongue member, as and for the purposes described.

3. In a shoe fastener, the combination with the shoe-top and a hook thereof, of a tongue member provided with an aperture 35 through which said hook extends and extending to each side of the hook, and a backing-plate secured at one end to the shank of said hook and at the other end to an end of said member.

4. In a shoe-fastener, the combination with the lacing hook and a backing-plate, of a tongue member comprising a spring plate which is secured near one of its ends to the backing-plate and is provided with an aperture 45 through which the neck of the hook extends, the part of the member which extends beyond the hook and opposite the end which is secured to said backing-plate being formed with recesses in its sides and in proximity of 50 the extremity.

In testimony whereof we affix our signatures in presence of two witnesses.

CHARLES H. CHANDLER.
